(57) CLAIM

I claim the ornamental design for a bracelet, as shown and described.

DESCRIPTION

FIG. 1 is a front perspective view of a bracelet, showing my new design in a connected configuration;

FIG. 2 is a front view of a Bracelet, showing my new design in a disconnected configuration;

FIG. 3 is a rear view thereof;

FIG. 4 is a top plan view thereof;

FIG. 5 is a bottom plan view thereof;

FIG. 6 is a left side elevation view thereof; and,

FIG. 7 is a right side elevation view thereof.

The broken lines shown in FIGS. 3, 6 and 7 illustrate portions of the bracelet which form no part of the claimed design.
